UNITED STATES PATENT OFFICE

WILLIAM B. CHAPMAN, OF JACKSON HEIGHTS, NEW YORK, ASSIGNOR, BY MESNE ASSIGNMENTS, TO THE COOPER-BESSEMER CORPORATION, OF MOUNT VERNON, OHIO, A CORPORATION OF OHIO

ASH REMOVING APPARATUS FOR GAS PRODUCERS AND THE LIKE

Application filed July 29, 1926. Serial No. 125,621.

The invention relates to the removal of ash from gas producers and gas generators, particularly in such manner as to permit the force of the blast within the generator to eject the ash therefrom.

The invention also relates particularly to gas generators and gas producers of the dry bottom type and involves the use of means for reducing the ash to such fine sizes as may be removed by fluid pressure, in combination with a receptacle disposed beneath the fire bed into which receptacle the ash falls and from which it is ejected with the aid of the blast pressure as above described.

The invention also involves a device to prevent arching over or clogging of the ash within the receptacle above mentioned and certain other features and advantages which will be in part obvious and in part specifically mentioned in the description hereinafter contained which, taken in conjunction with the accompanying drawings, discloses certain preferred embodiments of the invention. Such embodiments, however, are to be con-

ting to distribute the fuel evenly over the firebed and maintain uniform conditions of combustion. The agitating member is preferably surrounded by a water-cooled annular wear ring 4 provided with internal ribs 5, whereby any large clinkers which are stroked outwardly by the beam may be ground up between the ends of the beam and the ribs on this wear ring. As shown the ends of the beam are connected to a large gear 6 located underneath the wear ring 4 and supported by an anti-friction bearing member 7, the gear being driven in any suitable manner as by pinion 8, to turn the agitator.

As the agitating member rotates in the bottom of the firebed, it reduces the ash in that vicinity to sizes small enough to pass through restricted openings in grate 2 and the grate is so constructed as to be adjustable as regards the rate at which ash will fall through it. For example, the grate may be made up of sections movable with regard to each other whereby the adjustment of the one section will serve to obstruct more or less the passage

55

60

65

70

tion, whereby adequate opening for the blast is provided, regardless of the position to which the lower grate section is adjusted.

The ash falls through the grate as above described into an ash receptacle 18 illustrated in Fig. 1 as being of inverted conical shape and provided with a discharge opening 19 at its bottom which is closed by a gate 20 except when ash is being discharged from the receptacle.

The blast is supplied through a suitable opening 21 beneath the grate and since the agitating member grinds up the ash to such small sizes that it will pass through the restricted openings in the grate the pressure of the blast within receptacle 18 will be sufficient to force the ash out through opening 19 in the receptacle, when gate 20 is open. In most cases the pressure of the blast of air or air mixed with steam will be sufficient not only to eject the ashes but also to convey them through a pneumatic conveyor or the like to any desired point of discharge.

I prefer also to provide a device for preventing clogging or arching of the ash within receptacle 18, this device serving to maintain the ash in a loose condition whereby the pressure of the blast will be effective to discharge it. As shown, a rotating arm 22 is affixed to a central depending flange 23 on agitating member 3, a chain or the like 24 being attached to the arm 22 at one end and to a loose ring 25 at the other end whereby as the arm 22 turns around the chain tends to cut its way spirally through the ash receptacle 18 and break up any arches or stoppages in the ash.

In the present form of the invention the ash in receptacle 18 is also loosened up by means of radial fins 26 carried by cooling water pipe 27 which leads axially into the agitating member 3 and rotates with the latter, a rotary coupling 28 being provided underneath the fins 26 to connect between pipe 27 and a fixed cooling-water pipe 29 which passes through the wall of receptacle 18. It will be understood that a further cooling-water pipe 30 may be used in connection with the pipes above described for circulating the cooling water in accordance with known practice and it accordingly is not deemed necessary to describe this part of the construction in detail.

As the fins 26 turn around, the spaces immediately behind them tend to remain open, thus affording passageways through which the pressure of the blast may pass downward to the region of discharge opening 19 and act effectively to force the ash through the discharge opening. This is particularly necessary when large quantities of ash are allowed to accumulate before being discharged, as they tend to keep the blast pressure away from the point of discharge. At the same time the chain 24 turns around as above de-

scribed to keep the ash in a loose condition as it moves toward opening 19, stops or ledges 31 being provided on the fins 26 to prevent ring 25 from dropping down too far.

When the ash is ejected through opening 19 as above described, certain gases are entrained with it and I prefer to carry away the ash and gases from opening 19, by a conduit 32 which is shown in Fig. 1 as operated by fluid pressure through the medium of a steam injector nozzle 33, passing into the delivery end 34 of the conduit. When gate 20 is opened and steam under pressure passes through nozzle 33, the ash and entrained gases passing through opening 19 will be drawn into the delivery section 34 of conduit 32, along with any air which may pass in through the open end 35 of such conduit. Thus the entrained gases are prevented from escaping and the pressure of the blast in the producer does not scatter the dry ashes into unconfined spaces in ejecting them but aids in delivering them at any desired point.

The form of the invention shown in Figs. 4 and 5 is particularly adapted for use in water-gas generators which periodically are subjected to up and down blasts of air and steam. Fig. 4 shows only the bottom portion of an ash receptacle 18a, the ash within which is loosened by means of fins 26a and a chain 24a similar to members 24 and 26 above described, the receptacle 18a being provided with a discharge opening 19a, normally closed by a pivoted gate 20a which is operated by an arm 36 and permits the ash to pass into conduit 32a which also carries off the gases entrained with the ash.

An apparatus of the above nature, when used in conjunction with a water-gas generator, may be periodically operated in accordance with the cycle of the air and steam runs, as by providing a pneumatic cylinder 37 for operating the arm 36, this cylinder being actuated automatically during each period when the air blast is passing up through the generator whereby gate 20a is opened each time the ash in receptacle 18a is subjected to air blast pressure. Thus the ash will be ejected periodically in small quantities making the operation of the generator automatic and continuous insofar as the removal of ash is concerned. For pneumatic ash conveying it is particularly desirable that the ash ejection be in small quantities in order to prevent clogging.

While certain specific embodiments of the invention have been described it will be obvious that many changes may be made therein without departing from its principles as defined in the appended claims. The reference in the claims to gas generators furthermore should be understood as being made in a generic sense and hence including apparatus for making producer gas.

I claim:

1. In combination, a gas generator adapted to contain a fire bed and having an agitating member working in the bottom of the fire bed to reduce the ash to fine sizes, a receptacle disposed beneath the fire bed to receive the ash, means for introducing the blast for the firebed into said receptacle, said receptacle being provided with an ash discharge opening whereby the pressure of the blast within the receptacle forces the ash out through said opening, and fluid pressure operated means for conveying the ash and entrained gases away from said discharge opening, and means operating in the ash within said receptacle for preventing clogging of the ash therein.

2. In combination, a gas generator adapted to contain a fire bed and having means coacting with the fire bed for reducing the ash to fine sizes, a receptacle disposed beneath the fire bed to receive the ash, means for introducing the blast for the fire bed into said receptacle, said receptacle being provided with an ash discharge opening whereby the pressure of the blast within the receptacle forces the ash out through said opening, and means operating in the ash in said receptacle for affording effective blast pressure in the region of said discharge opening.

3. In combination, a gas generator, adapted to contain a fire bed and having means coacting with the fire bed for reducing the ash to fine sizes, a receptacle disposed beneath the fire bed to receive the ash, means for introducing the blast for the fire bed into said receptacle, said receptacle being provided with an ash discharge opening whereby the pressure of the blast within the receptacle forces the ash out through said opening, and means operating in the ash of said receptacle for affording effective blast pressure in the region of said discharge opening, said means comprising one or more rotary members turning in the ash.

4. In combination, a gas generator adapted to contain a fire bed and having an agitating member working in the bottom of the fire bed to reduce the ash to fine sizes, a receptacle disposed beneath the fire bed to receive the ash, said receptacle being provided with an ash discharge opening whereby the pressure of the blast within the receptacle forces the ash out through said opening, a rotary member for supplying cooling water to said agitating member, said rotary member being disposed in said ash receptacle and one or more fins carried by said rotary member for operating in the ash.

5. In combination, a gas generator adapted to contain a fire bed and having an agitating member working in the bottom of the fire bed to reduce the ash to fine sizes, a receptacle disposed beneath the fire bed to receive the ash, means for introducing the blast for the

fire bed into said receptacle, said receptacle being provided with an ash discharge opening, and means operating in the ash in said receptacle for loosening the ash therein to cause the blast pressure to force the ash through said discharge opening.

6. In combination, a gas generator adapted to contain a fire bed and having an agitating member working in the bottom of the fire bed to reduced the ash to fine sizes, means for blasting the fire bed, a receptacle subject to the blast pressure and disposed beneath the fire bed to receive the ash, an arm adjacent said receptacle and connected to rotate with said agitating member, and means carried by said arm for loosening the ash within said receptacle, said receptacle being provided with an ash discharge opening whereby the pressure of the blast may force the ash out through said opening.

7. In combination, a gas generator adapted to contain a fire bed and having means coacting with the fire bed for reducing the ash to fine sizes, a receptacle disposed beneath the fire bed to receive the ash, means for introducing the blast for the fire bed into said receptacle, said receptacle being provided with an ash discharge opening whereby the pressure of the blast within the receptacle forces the ash out through said opening, and means providing a passageway through the ash in said receptacle to make the blast pressure effective in the region of said discharge opening.

In testimony that I claim the foregoing, I have hereunto set my hand this 24 day of July, 1926.

WILLIAM B. CHAPMAN.
